Des. 207,597
Patented May 9, 1967

207,597

COMBINED EXTENSIBLE EXAMINATION LAMP AND CABINET THEREFOR

Marcus Bodian, Los Angeles, Calif., assignor to Sunbeam
Lighting Co., Inc., Los Angeles, Calif., a corporation
of California

Filed Sept. 12, 1966, Ser. No. 3,807

Term of patent 14 years

(Cl. D48—20)

Fig. 3.

Fig. 4.

Fig. 5.

Fig. 6.

FIG. 1 is a perspective view of the combined extensible examination lamp and cabinet therefor showing my new design;

FIG. 2 is a top plan view of the same with arms extended;

FIG. 3 is a front elevational view of the same with arms closed;

FIG. 4 is a top plan view of the same with arms closed;

FIG. 5 is an end elevational view taken from the position of line 5—5 of FIG. 3; and

FIG. 6 is an end elevational view taken from the position of line 6—6 of FIG. 3.

I claim:

The ornamental design for a combined extensible examination lamp and cabinet therefor, as shown and described.
